UNITED STATES PATENT OFFICE

EUGENE VAN NOTE, OF JERSEY CITY, NEW JERSEY

RUDDER

Application filed February 19, 1930. Serial No. 429,503.

This invention relates primarily to means for steering aeroplanes but its principles may be applied to other vehicles.

A principal object of the invention is to provide means for steering aeroplanes so as to control their movement in any direction.

Another principal object is to maintain the rudders in such manner as to insure their non-resistance to wind when not influenced by the steering controls.

Another object is to enable the operator of the machine to manipulate the steering mechanism without unduly taking his attention away from the other controls of the machine.

Other objects will be apparent from reading this specification in conjunction with the accompanying drawings.

20 In the drawings,

Figure 1 is a side view of an aeroplane embodying my invention;

Figure 2 is a fragmentary sectional enlargement of the same;

25 Figure 3 is a plan view of Figure 1 looking at the same from the top; and

Figure 4 is a fragmentary sectional view of Figure 3 showing part of the operating mechanism of the horizontal rudder.

30 Referring now in detail to the drawings, 5 represents the fuselage of an aeroplane, 6 the cab, 7 the operator's seat, 8, 8 the vertical rudders, and 9 the horizontal rudder, 10 the propeller, 11 the wings, and 12

35 the landing gear.

The vertical rudders 8, 8 are arranged parallel to each other and are mounted to swing on the vertical rods 13, 13 supported in the body of the aeroplane. These vertical rudders are connected to each other by

40 the pivotal links 14, 14, in such manner as not to interfere with the free arcuate movement of the same so as to constantly maintain a substantially parallel position to each other. These vertical rudders 8, 8 are pref-

45 erably mounted on the rods 13, 13, off their vertical centers so as to dispose the longer sides of the rudders toward the rear, thus tending to hold said rudders in a normally

50 parallel position with the fuselage when the

aeroplane is in operation and when uninfluenced by manipulation of the steering wheel 21.

A pulley 16 is provided on which is mounted to move therewith a bracket 15, pivoted to the outer end of which are the links 18, 18, which links are in turn pivoted to the respective blades of the rudder 8, 8.

55 Located in the cab 6 is the steering post 20 on which is integrally mounted at the upper end the steering wheel 21 and at the lower end the pulley 22. A cable 23 extends over and connects the pulleys 16 and 22 so as to provide operative connection between the steering wheel 21 and the vertical 60 rudders 8, 8.

65 The horizontal rudder 9 is also preferably mounted off center, the balance of weight being at the rear. This horizontal rudder is adapted to move with the horizontal rod 25 to which it is secured. A bellcrank 24 is preferably keyed at its angle to the rod 25, one end of said bellcrank being secured in the rear section of the horizontal rudder at 25, while the other end of this bellcrank is pivotally connected at 26 to a link 27 which in turn is pivotally connected to the pulley 28. A cable 29 extends over the pulley 28, its ends being connected to the equalizer bar 30 pivoted at 31. A link 32 connects this 70 equalizer bar to the lever 33 operated from the handle 34, and the rudder 9 may be maintained in any desired position by the cooperation of the quadrant 35 with the pawl 36 controlled by the handpiece 37.

75 In operation, both the vertical rudders and the horizontal rudder when not influenced by the controls in the cab are normally maintained in a substantially parallel position with the fuselage of the plane and 80 offer little resistance to wind when the plane is in motion. If it is desired to change the horizontal direction of the plane, the steering wheel 21 is manipulated by the operator, which action will control the movement of 85 the cable 23, which in turn operates on the pulley 16, through it the bracket 15, the links 18 and the blades of the vertical rudder 8, 8. When a banking movement or a 90 vertical movement is desired, the operator 95

100

will manipulate the lever 33 which changes the position of the equalizer bar 30 and pulls at the appropriate end of the cable 29 which in turn operates the pulley 28 and through it successively the link 27, bellcrank 24 and horizontal rudder 9.

I have shown and described what I believe to be the best embodiment of my invention. I do not wish to be limited in patent protection, however, to the embodiment shown, but what I desire to secure by Letters Patent is set forth in the accompanying claims.

I claim:

1. In steering mechanism, a plurality of rudder blades mounted to rock intermediate their ends, a plurality of links hingeably connected at their ends to adjacent rudder blades, a control bar hingeably connected to adjacent rudder blades, and means for sliding said control bar in a longitudinal direction and maintaining the rudder blades in a substantially parallel position to each other.
2. In steering mechanism, a plurality of rudder blades mounted to rock intermediate their ends, a plurality of links hingeably connected at their ends to adjacent rudder blades, a control bar hingeably connected to adjacent rudder blades, an arcuating member and a link, said link being hingeably connected to said arcuating member, a flexible connection attached to said arcuating member and means for activating said arcuating member through said flexible connection.
3. In steering mechanism, a rudder mounted to rock intermediate its ends, a bell crank adapted to rock said rudder, an equalizer bar pivotally mounted intermediate its ends and adapted to be operated by the feet of the operator, and means for rocking the aforesaid bell crank, said means being flexibly connected to and operated from said equalizer bar.

In testimony whereof I have affixed my signature to this specification.

EUGENE VAN NOTE.
